UNITED STATES PATENT OFFICE

LOUIS LAMER, OF RAMSEY, NEW JERSEY

PLATE GLASS STORE FRONT CONSTRUCTION

Application filed April 29, 1930. Serial No. 448,355.

The present invention relates to building construction, and has particular reference to an improved construction of store front for accommodating and supporting large plate

5 glass panes or panels.

Another object of the present invention is to provide an improved store front construction wherein drainage and ventilation between the inner and outer sides of the plate 10 glass is provided for, and wherein the construction admits of the introduction of the large plate of glass into the frame or store front from either side of the structure, and wherein all of the fastening or securing 15 means employed in connection with the construction are located in concealed position and are accessible only from the inner side of the plate of glass.

The invention still further aims to provide a store front construction embodying the 20 above characteristics, and which at the same time imparts a strictly architectural hollow metal construction, and which provides a construction which in assembling and removing 25 from the store front saves considerable labor, insures accuracy, and enables the glasier to set the glass from the outside or the inside of the store show room, as conditions permit.

With the foregoing and other objects in 30 view, which will be apparent as the description proceeds, the invention resides in the construction and arrangement of parts, as hereinafter described and claimed, it being understood that changes can be made within 35 the scope of what is claimed, without departing from the spirit of the invention.

The invention is illustrated in the accompanying drawings:

Figure 1 is a fragmentary perspective view 40 partly in section of a store front constructed according to the present invention and showing a large plate of glass mounted therein.

Fig. 2 is a fragmentary sectional view taken through the same.

Fig. 3 is a detail fragmentary perspective view, partly in section, of the inner base sash rail.

Fig. 4 is a similar view of the bead or cover plate for the inner sash rail, and

50 Fig. 5 is a detail horizontal section taken

through the improved store front substantially on the line 5—5 of Fig. 2 and showing the means for anchoring the inner and outer rail portions of the sash.

Referring now to the drawings, 10 designates a panel which is composed of a large plate of glass of the usual thickness and which may be of any desired size for closing in a store front or a show window. The pane of glass is adapted to seat at its lower end upon the upper flat surface portion of a sill 11, and the sill 11 is mounted in turn upon the rails or channel strips comprising the sash construction of this invention, the holes being supported upon a casing or outer covering 60 plate 12 of sheet metal or the like which provides the finish for the lower wall or base portion 13 of the show window or store front.

The inner sash member comprises a longitudinal rail or channel strip shown to advantage in Fig. 3 and which has a flat base portion 14 provided along its inner edge with a vertically disposed flange 15 adapted to bear against an inner finishing strip 16 of wood or the like, as shown in Fig. 1, and which is returned outwardly for substantially half the height of the flange 15 to provide a double thick upper edge portion thereof for reinforcing the top portion of the flange 15.

The returned parts of the flange 15 extend 70 forwardly and horizontally in substantially parallel relation to the base portion 14 to provide a ledge plate 17 of substantial depth and which at its forward edge is provided with an upturned short shoulder or flange 75

18 adapted to seat in and against a correspondingly cut out rabbet formed in the inner upper edge of the sill 11. As shown in Figs. 3 and 5, this shoulder flange 18 is provided

80 at spaced points throughout its length with longitudinal slots 19 for a purpose which will hereinafter appear. The ledge plate 17 is provided with a longitudinal row of openings 20 which serve for the purposes of ventilation and drainage. The shoulder flange 85

19 is also provided at suitable points with screw receiving openings 21 for receiving therethrough the intermediate portions of securing screws 22 which are adapted to pass 90 downwardly and forwardly into the sill 11 100

beneath the lower edge of the plate of glass 10.

The cover or bead strip is in the form of an arched or transversely curved plate, as shown particularly in Figs. 1, 2 and 4. This plate, designated at 23, is of suitable width adapted to rest at its lower edge upon the ledge plate 17 at the foot of the reinforced upper portion of the flange 15 and at its upper edge adapted to yieldingly bear against the inner side of the plate of glass 10 so as to yieldingly bind against the latter and hold it in the sash. It will be noted that the intermediate longitudinal portion of the plate 23 is provided with a longitudinal row of openings or apertures 24 for the purpose of ventilating the channel formed above the ledge plate 17, and also for the purpose of receiving the upper end portions of the screws 22 where such screws 22 are located. There are a greater number of openings 24 than there are screws 22 so that a number of the openings 24 are left free and unobstructed for the passage of air, water and the like through the cover plate or strip 23. This cover plate or strip 23 may be given any suitable transverse curvature providing the necessary resiliency and strength, and so as to properly locate the upper and lower edges of the plate to bear respectively against the reinforced portion of the flange 15 and against the inner side of the plate of glass 10. This inner sash member is adapted to be seated upon the covering plate 12 of the wall and to be secured thereto by short screws 25 which pass downwardly through the base portion 14 of the inner sash rail in openings 26 thereof and into the wall or base portion 13. Longer screws 27 are also provided in suitable number which pass downwardly through the opening 20 in the ledge plate 17 and through adjacent registering portions of the base portion 14 and finally into the base portion 13 of the wall.

The sill 11 is seated upon the base portion 14 of the inner sash rail directly over the line of small screws 25, or substantially midway between the inner and outer edge portions of the base 14 of the rail. The base 14 is adapted to seat flat against the covering plate 12 of the wall 13, and the outer edge portion of the base of the rail is offset upwardly to substantially the thickness of the base portion 14 to provide a locking lip 28 for interlocking engagement with the outer sash member.

The outer sash member comprises a longitudinal rail having its intermediate longitudinal portion returned upon itself to provide a ledge 29 of double thickness which is disposed in substantially the same horizontal plane as the ledge 17 and which is anchored or secured thereto by a desired number of straps 30. The inner ends of the straps 30 are secured beneath the edge of the long screws 27 so as to bind the inner ends of the straps 30 against the upper surface of the

ledge 17. The straps 30 extend rearwardly through the slots 19 formed in the shoulder flanges 18 of the inner sash rail, and the straps 30 also pass through correspondingly formed slots or recesses provided in the upper portion of the sill 11 as shown to advantage in Fig. 1. The outer end portion of each strap 30 is secured flat against the upper side of the ledge 29 by means of an individual nut and bolt 31 shown in Fig. 2, and the strap 30 thus serves to secure the inner and outer sash members together and at the opposite sides of the plate of glass 10.

The upper edge portion of the outer sash member constitutes a cover plate or bead which is transversely curved into desired configuration, and which extends upwardly from the outer end or edge of the ledge 29 and is rolled gradually inward and upwardly to terminate in a resilient lip 32 adapted to bear yieldingly against the outer side of the plate of glass 10. It will be noted that the lip 32 corresponds substantially in height to the upper edge portion of the cover plate 23 so that the two yieldable members operate against one another to yieldingly hold the plate of glass 10 upon its seat on the upper edge of the sill 11. It will be noted from Fig. 2 particularly, that the upper flat edge portion of the sill 11 is relatively wide as compared with the thickness of the plate of glass 10 so as to not only accommodate the plate of glass 10 of different thicknesses, but to also admit of the relative shifting of the lower edge of the plate of glass 10 and the upper edge portion of the sill 11 without unseating the plate of glass.

The ledge 29 of the outer sash member extends outwardly beyond the resilient lip portion 32 and provides a base shoulder 33 which not only gives a fanciful configuration to the outer sash member, but also provides a substantial means for supporting the ledge 29 and the lip 32 in position at the outer side of the pane of glass. The rail which forms the outer sash member is turned downwardly from the shoulder 33 to provide an exterior vertical flange 34 which terminates in an in-turned lip 35 which is adapted to seat upon the plate 12 and engage beneath the locking lip 28 of the rear rail member. The vertical flange 34 is provided with a suitable number of venting and draining openings 36 which are adapted to open at the bottom edge portion of the flange 34 and which cooperate with suitable slots or passages 37 formed through the lower edge portion of the sill 11, as shown in Figs. 1 and 2. There is thus established a means of ventilation and drainage between the inner and outer sash members through the ledges 17 and 29 and also through the sill 11.

In installation, the inner sash member may be mounted upon the wall 13 without the cover or bead plate 23, and before the outer

sash member is properly positioned, the plate glass panel 10 may be seated upon the sill 11 and then the straps 30 secured through the outer sash member and inserted inwardly 5 through the upper edge portion of the sill 11, through the straps 19 and be secured in place beneath the screw 27.

It is of course understood that various changes and modifications may be made in 10 the details of construction and design of the above specifically described embodiment of this invention without departing from the spirit thereof and restricted only by the scope of the following claims.

15 What is claimed is:

1. In store front construction for supporting plate glass, an inner channel member having a base portion adapted to extend beneath the glass and provided at its inner 20 edge with an upstanding flange returned upon itself to provide a reinforced upper edge for the flange and extending horizontally in spaced relation above the base portion to provide a channel part, a sill seated upon the 25 base portion and engaging beneath said channel part and adapted to support the lower edge of the plate glass, an outer rail having a vertical flange with an inturned lip at its lower end adapted to interlock with the base 30 portion of the inner rail and provided at the upper edge of said vertical flange with an inwardly extending ledge arranged substantially in register with said channel portion, said outer rail having an upwardly curved 35 resilient lip adapted to engage against the outer side of the plate glass, a plurality of straps secured to said ledge and extending inwardly through the sill and overlapping the channel portion of the inner rail, securing 40 means engaging downwardly through said strap the channel portion and the base of the inner rail for interlocking the parts together, and a cover plate arranged diagonally between said channel portion of the 45 inner rail and the inner side of the plate glass for housing the securing means and maintaining the plate glass upon the sill.

2. In store front construction for supporting plate glass, inner and outer rails, said inner rail having a channel portion and provided therebeneath with a base portion adapted to rest upon the wall of a building, a sill mounted on said base portion and engaging beneath said channel portion and adapted to 50 support the lower edge of a plate of glass, an outer rail having a vertical flange with an inturned lip adapted for interlocking engagement with said base portion and provided at the top of said flange with an inwardly extending ledge arranged opposite to the channel portion of the inner rail and further provided with a resilient curved lip extending upwardly from the outer portion of said ledge for engagement against the outer side 55 of the plate of glass, a plurality of straps se-

cured to said ledge and engaging through said sill and into overlapping relation with the channel portion of the inner rail, anchoring screws extending downwardly through the inner ends of said strap, said channel 70 and base portions of the inner rail and into the wall for interlocking all of the parts together and upon the wall, and a cover plate seated in said channel portion of the inner rail adapted to enclose said fastening means 75 and adapted to engage the inner side of a plate of glass for maintaining the same upon said sill.

3. A sash construction comprising two sash members, one having a base with which 80 the other is interengaged, a sill resting on said base to support a pane of glass, said members having portions extending toward one another and contacting with the opposite sides of said sill, resilient portions on said 85 members to bear against the opposite surfaces of said pane, and securing means connecting the firstnamed portions.

4. A sash construction comprising two sash members, one having a base with which 90 the other is interengaged, a sill resting on said base to support a pane of glass, said members having portions extending toward one another and contacting with the opposite sides of said sill, resilient portions on said 95 members to bear against the opposite surfaces of said pane, and straps overlapping and secured to the firstnamed portions.

5. A sash construction comprising a sill for supporting a pane of glass and having a 100 rabbit, a sash member having a base portion and a channel portion above same and seated in said rabbit, securing means fastening said channel portion in said rabbit, and a plate seated at one edge in the corner of the channel 105 portion opposite to the pane and having its other edge arranged to bear against one surface of the pane.

6. A sash construction comprising an inner sash member having a base portion and a 110 channel portion above the base portion, a sill for supporting a pane of glass seated on said base portion and having a rabbit in which said channel portion is seated, an outer sash member engaging said base portion and having an upper resilient lip to bear against the outer surface of the pane, a cover plate seated in the corner of the channel opposite to said pane and adapted to bear at its upper edge against the inner surface of the pane, and securing means connecting the outer sash member and said channel portion.

7. A sash construction comprising an inner sash member having a base portion and a channel portion above the base portion, a sill for supporting a pane of glass seated on said base portion and having a rabbit in which said channel portion is seated, an outer sash member engaging said base portion and having an upper resilient lip to bear against the 125 130 135

outer surface of the pane, a cover plate seated in the corner of the channel opposite to said pane and adapted to bear at its upper edge against the inner surface of the pane, the outer sash member having a doubled portion, and straps overlapping and secured to said doubled and channel portions.

8. A sash construction comprising a base, a sill on the base for supporting a pane of glass, a sheet metal sash member having a raised doubled portion contacting with one side of said sill and having a resilient lip to bear against one surface of the pane, and straps extending through the sill and overlapping and secured to said portion and to the base at the opposite side of the pane of glass.

In testimony whereof I hereunto affix my signature.

LOUIS LAMER.
